DESIGN FOR A BOTTLE

Robert H. Barrett, Rochester, N. Y.

Application May 6, 1938, Serial No. 77,045

Term of patent 3½ years

To all whom it may concern:

Be it known that I, Robert H. Barrett, a citizen of the United States, residing in the city of Rochester, county of Monroe, and State of New York, have invented a new, original, and ornamental Design for Bottle, of which the following is a specification, reference being had to the accompanying drawing forming part thereof, in which

Fig. 1 is a plan view of the bottle showing my new design; and

Fig. 2 is a perspective view thereof.

I claim:

The ornamental design for a bottle, as shown.

ROBERT H. BARRETT.
